UNITED STATES PATENT OFFICE.

EMERY M. HAMILTON, OF NEW YORK, N. Y.

TYPE-WRITING MACHINE.

SPECIFICATION forming part of Letters Patent No. 430,771, dated June 24, 1890.

Application filed February 10, 1890. Serial No. 339,766. (No model.)

To all whom it may concern:

Be it known that I, EMERY M. HAMILTON, of the city, county, and State of New York, a citizen of the United States, have invented 5 certain new and useful Improvements in Type-Writing Machines, of which the following is a full, clear, and exact description, reference being had to the accompanying drawings, forming part of this specification.

10 My invention relates to type-writing machines of the class known as "type-bar" machines, and to a machine of that class in which the type-bar is provided with a bearing by which it is pivotally mounted on a support 15 that is adapted to force a face on the type-bar to contact with an opposed face on the support when the type-bar is vibrated in the direction to effect printing.

My invention consists in the combination, 20 with a type-bar support or bracket having an aligning face and a type-bar having a face opposed and preferably parallel to and guided by said aligning face, of a conical or tapered bearing rigidly fixed to said support or bracket, by which the type-bar is pivotally mounted 25 on the support or bracket, whereby as the type-bar is vibrated on said bearing in the direction to effect printing the type-bar face will be automatically forced to contact with 30 the aligning face on the support or bracket, and the type-bar will thus always vibrate on said bearing in one and the same plane when effecting printing; and my invention further consists in the combination, with 35 a series of radially-arranged type-bars, of a corresponding series of radial supports or brackets, each said support or bracket being provided with a conical or tapered bearing rigidly fixed to and by which the type- 40 bars are severally pivotally mounted on the supports or brackets individually throughout the series, and each said support or bracket, carrying its single type-bar on said conical or tapered bearing, being individually ad- 45 justable radially in the series, whereby while wear on each or any of the type-bar pivotal bearings will be automatically compensated for by the described taper of the bearings, so that the type-bars will each always vibrate in 50 one and the same plane when vibrated on said bearings in the direction to effect printing, as hereinbefore stated, such wear upon

the conical or tapered bearings may be compensated for by said radial adjustment of the support or bracket to which said bearing is 55 fixed, so that the type carried by the type-bar may always strike at one and the same point.

Figure 1 is a plan of a circular series of radially-arranged type-bar supports or brackets and their type-bars containing my invention, and showing two key-levers and connected mechanism. Fig. 2 is a vertical longitudinal section of a type-writing machine containing my invention. Fig. 3 is a plan of a type-bar and its support or bracket de- 65 tached, containing my invention. Fig. 4 is a similar view of the same, partly in section. Fig. 5 is a side elevation of the parts shown in Figs. 3 and 4; and Fig. 6 is an end view of the support or bracket, partly in section. 70

The features of my present invention are shown in connection with certain novel features relating to the key-levers and to the lever-actuating mechanism generally and in connection with certain novel features re- 75 lating to the type-bar brackets and their arrangement in the machine; but as such features of the lever movement, key-levers, and type-bar brackets constitute no part of my present invention they are not described 80 herein, but are reserved herefrom, and are fully set forth in other applications for Letters Patent—to wit, Serial No. 339,771, relating to the lever movement, &c., filed simultaneously herewith, and Serial No. 343,108, 85 relating to the type-bar brackets, filed March 8, 1890, of which they are severally the subject-matter.

A is a type-bar, and B is a type-bar support or bracket upon which the type-bar is mounted 90 to vibrate by means of a pivotal bearing. The support B is provided with an aligning face b, and the type-bar A has a face a, the said faces being preferably planes, as shown, and desirably located around the pivotal bearing, 95 and with the face a opposed and preferably parallel to the face b, as shown.

C is a conical or tapered bearing, which is fixed rigidly upon the support or bracket B, and is preferably constituted by a pin or stud 100 seated fixedly in the bracket, as shown, and having the described conical head with the taper thereof in the direction toward the face b of the support or bracket. The type-bar A

has an aperture corresponding to the conical or tapered bearing C, whereby it is mounted on said bearing. Variations in the form or general outline of the tapered bearing may be made without departing from my invention so long as the general direction of the taper is toward the said aligning face b on the support or bracket. Now, it is evident that when the type-bar is vibrated in the direction to effect printing—as, for example, by means of a link D, connecting the type-bar to the usual key-lever, as illustrated in Figs. 2 and 5—the described fixed tapered pivotal bearing C will operate to automatically force or crowd the type-bar face a to and in contact with the aligning face b on the support or bracket B, so that the type-bar in its vibration will be guided by the face b, and will hence always vibrate in one and the same plane when vibrated in the direction to effect printing.

The brackets B, each carrying on a conical or tapered pivot fixed rigidly thereto, as described, a type-bar, are, in further carrying out my invention, arranged radially in a circular or equivalent series in a type-writing machine, and each bracket is adapted to be radially adjustable individually in the series, which may be accomplished by clamping all the brackets between two annular plates E and E', held together by screws e, as shown. It is evident that by means of this arrangement, while each type-bar will always vibrate on its fixed conical bearing in one and the same plane, any wear upon said bearing being automatically compensated for by the taper of the bearing, as described, so far as the forcing of the face on the type-bar to contact with the aligning face on the bracket is concerned, such wear on each tapered bearing may be compensated for, in the direction lon-

gitudinally of the type-bar by the radial adjustability of the bracket to which said bearing is fixed, so that the type carried by the type-bar having vibration always in the same plane, as set forth, may always strike at one and the same point.

What I claim as my invention, and desire to secure by Letters Patent, is—

1. In a type-writing machine, the combination, with a type-bar support or bracket provided with an aligning face and a type-bar having a face which is opposed to and guided by said aligning face on said support, of a conical or tapered pivotal bearing fixed rigidly to said support, by which said type-bar is mounted to vibrate on said support or bracket, substantially as and for the purpose set forth. 50

2. In a type-writing machine, a vibratory type-bar having a conical or tapered bearing, 60 in combination with a conical or tapered pivot fixed rigidly to a support and an aligning face on said support around said pivot parallel and opposed to a corresponding face on the type-bar, substantially as and for the purpose 65 set forth.

3. In a type-writing machine, the combination, with a series of radially-arranged type-bars, of a corresponding series of radial supports or brackets, each said support or bracket 70 being provided with a conical or tapered bearing fixed rigidly therein, by which the type-bars are severally pivotally mounted on said supports or brackets, and said supports or brackets being adapted to be adjustable radially individually in the said series, substantially as and for the purpose set forth. 75

EMERY M. HAMILTON.
